UNITED STATES PATENT OFFICE

103,307

DESIGN FOR A FUNNEL STAND

Harvey Cory, Chicago, Ill.

Application January 11, 1937, Serial No. 67,003

Term of patent 14 years

To all whom it may concern:

Be it known that I, Harvey Cory, a citizen of the United States, residing at Chicago, in the county of Cook and State of Illinois, have invented a new, original, and ornamental Design for a Funnel Stand, of which the following is a specification, reference being had to the accompanying drawing forming a part thereof wherein the figure is a perspective view of a funnel stand showing my new design.

I claim:

The ornamental design for a funnel stand, as shown.

HARVEY CORY.
